UNITED STATES PATENT OFFICE.

FREDRICK SUMNER PALMER, OF BOSTON, MASSACHUSETTS.

FIRE-ALARM AND ANNUNCIATOR SYSTEM.

SPECIFICATION forming part of Letters Patent No. 530,648, dated December 11, 1894.

Application filed March 24, 1894. Serial No. 504,940. (No model.)

To all whom it may concern.

Be it known that I, FREDRICK SUMNER PALMER, a citizen of the United States, residing at Boston, in the county of Suffolk and State of Massachusetts, have invented certain new and useful Improvements in a Combined Fire-Alarm and Annunciator System; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

This invention relates to electric systems employed for sounding an alarm, either in the event of a fire or to serve as a call, such as is covered by the term annunciator, which instrument is in very common use in hotels or other public places.

The object of my invention is to enable an annunciator system in which a push-button is employed, to be connected with and joined electrically with a fire-alarm system, containing a transmitter, the purpose of my invention being primarily to save the cost of double wiring hitherto necessary; in other words in lieu of having a separate system of wires for the annunciator system and also one for the fire system, to employ the latter wires as a circuit.

The drawings represent in Figure 1 a combined fire-alarm and annunciator system under my invention, the fire-alarm being shown only in diagram, as necessary for the proper illustration of my invention. Fig. 2 shows an enlarged view of the thermostats together with a push-button and all represented in their normal positions.

As before premised, it is very desirable to employ a push-button on a call system in connection with an automatic fire-alarm circuit, and thus enable a person to use the fire system for ordinary wants, but further to permit the fire system to remain inactive except at such times when fire may occur.

My invention may be applied to any fire alarm system having an inner and outer line of wiring, in connection with thermostats which serve to short-circuit said wires should a fire take place. In the present instance I have applied my invention to a system fully

described in United States Letters Patent No. 502,889, issued to me on the 8th day of August, 1893.

In the drawings I have shown the fire alarm system applied to two floors of a building the lower one presumably a store, the second floor containing suites of rooms as indicated by the broken lines in Fig. 1. The outer wire *a* is common to both floors, while separate inner wires *b* *c* are used for different floors. *A* represents test clock. *D* is a magnet. *E* is a test switch; *H*, vibrating bell at door of building; *I*, battery for fire system; *J*, battery for gong; *K*, in engine house; *L*, transmitter; *M*, fire alarm drop on the building to indicate individual floors. Various binder posts 1, 2, 3, 5, 6, 8, 9, 10, 15, 16, 17 serve to connect various parts of the system, as will be briefly hereinafter described.

In the normal condition starting at the positive side of the open circuit battery *I*, to binder post 15, the first path is to magnet *Q*. This path is open at the dotted spring 11'. Hence the current takes the path to spring 9', thence to 9², to magnet *D* of the transmitter, to spring 4². Here the current separates passing to binder posts 5 and 6 of the common or outer wire *a*. This constitutes the path of the positive current. From the negative side of the battery *I*, the circuit goes to binder post 1, vibrating bell *H*, to post 2, where it distributes itself over the wires *b* *c* of the several floors.

In the event of a general fire the thermostats *d*, *d'*, create a short-circuit between the wires *a* *b* and *a* *c*. Now for example assume the fire is in the second floor and the thermostat *d'* is in operation. The current now passes over the battery *I*, to post 15, through springs 9', 9², to magnet *D*, moving armature and releasing transmitter *L*, which causes four blows to be sounded on the gong *K*, showing box 4 at indicator in engine house. From magnet *D*, the current goes to springs 4² 4', binder posts 5 or 6, and common wire *a*, through thermostat *d'*, to binder post 9 or 10, the path offering the least resistance; from post 10 to drop *M*, indicating second floor; from thence to post 3, to spring 2' 2², to spring 1², 1', vibrating bell *H*, post 1, and negative side of battery *I*, thus completing the circuit.

Thus having briefly indicated the operation of a fire alarm circuit, I will now show my invention as applied thereto, and in the second floor, the respective rooms of which I 5 have indicated at $s^1 s^2 s^3 s^4$.

In connection with the fire alarm thermostats is combined a second series of thermostats $e^1 e^2 e^3$. A push-button B. is united to the outer wire a . Wires 20', 20², 20³ extend to 10 the office annunciator N. with a vibrating bell T. while a common wire 21 extends to a secondary battery C. This is joined to the outer wire a of the fire alarm system by the spring 4' 4². The thermostats $e^1 e^2 e^3$ on the 15 annunciator system are not arranged to short-circuit with the inner wires of the fire system, but have a loop wire 23' 23² 23³, to binding posts 24' 24² 24³. Hence in my invention as designed for hotel purposes and 20 applied to a fire alarm system, two thermostats are employed in each room and they may be placed under one rosette 25. A guest in a room s^2 calls for ice water. The push-button is closed and the current passes from 25 the battery C. to outer wires a , to push-button B; thence to hotel annunciator N. indicating room s^2 , through the bell T. to battery C; thus completing the circuit and with no disturbance of the fire alarm system. In the event 30 of a fire in said room s^2 the action of the fire alarm system is identical with that heretofore described, the thermostat d^2 short-circuiting the wires $a c$; but furthermore, the second thermostat e^2 closes the annunciator 35 system by aid of loop wire 23², the same as if the push-button had been operated. Hence the following results are accomplished simultaneously: the calling of the fire department to building 4; operating the drop M. indicating 40 second floor; ringing bell H., operating drop 2 at annunciator N, ringing the bell, and calling attention to the fact that there is a fire in room 2 second story. In this way the occupants of the building are enabled to

make an attempt to extinguish the fire before the arrival of the fire department. 45

What I claim is—

1. In combination with a fire alarm system, a call system, and independent batteries for each system, two thermostats electrically 50 united with the fire system, one thermostat being arranged to short-circuit the battery in the fire system through said system, the other thermostat to short-circuit the battery in the call system through the annunciator apparatus of said system, and through the fire system in part, substantially as described. 55

2. The combination with a fire alarm system having inner and outer wires, a battery therefor, and thermostats which short-circuit said 60 wires, of a second call system, a battery therefor, annunciator apparatus, a wire which unites the outer wire of the fire system with the call system, wires from the call system to the several rooms of a building, and room 65 thermostats which electrically join the fire alarm system with the individual room systems to operate the call system, substantially as stated.

3. A fire alarm system having inner floor 70 wires, a single outer wire, a battery therefor, and thermostats which short-circuit the inner and outer wires in time of danger, combined with a call system, a battery for this system, wires to various rooms, annunciator apparatus, a wire therefrom to the battery, and thermostats in the rooms which are joined to outer fire alarm wire, and means to electrically unite such thermostats with individual call wires in their respective rooms, substantially as explained. 75

In testimony whereof I affix my signature in presence of two witnesses.

FREDRICK SUMNER PALMER.
